ATTORNEYS

UNITED STATES PATENT OFFICE.

GEORGE R. UNKEFER, OF CLEVELAND, OHIO, ASSIGNOR OF ONE-HALF TO
HARRY J. MCKINNIE, OF SAME PLACE.

THREAD-CUTTER.

SPECIFICATION forming part of Letters Patent No. 553,439, dated January 21, 1896.

Application filed May 16, 1895. Serial No. 549,583. (No model.)

To all whom it may concern:

Be it known that I, GEORGE R. UNKEFER, a citizen of the United States, residing at Cleveland, in the county of Cuyahoga, State of Ohio, 5 have invented certain new and useful Improvements in Thread-Cutters; and I do hereby declare the following to be a full, clear, and accurate description of my said invention, such as will enable others skilled in the 10 art to make and use the same.

The object of my invention is a simple, inexpensive device that can readily be attached to a spool of thread and be used for cutting the thread, and as a convenience save breaking the thread or using a separate instrument with which to cut the thread, and which will not interfere with putting the spool over a spindle on a sewing-machine while the thread-cutter is in position in the spool.

20 My invention consists in the construction and combination herein described and defined in the claims.

In the drawings, Figure 1 is a perspective of my improved thread-cutter. Fig. 2 is a 25 front elevation of the same. Fig. 3 is a side elevation. Fig. 4 shows the same in position in a longitudinal section of a spool, and Fig. 5 illustrates the form of blank from which my device is formed.

30 In the manufacture of my invention, I first cut a blank substantially of the form illustrated by Fig. 5, from a piece of sheet steel or other metal. Said blank A is rectangular, with preferably rounded corners to relieve 35 it of any sharpness, to avoid cutting the hands of the user and to give the device a neater appearance. Projecting from the body A is an arm A' having a turned end A". The sharp angle a forms the cutting-notch. The 40 body part A is bent to the form of an open split cylinder of a larger diameter than the

diameter of the hole in a thread-spool, and forms an expansible spring to hold the cutter to the spool with the cylindrical spring open through from end to end, so that a spool with 45 the cutter in position may be put over a spindle on a sewing-machine.

When the cutter is in use, the cylindrical body part A is compressed by the hand so that it will enter the hole in the spool B. The expansibility of the cylinder will keep the cutter in position in the spool. The arm A' is bent outwardly from the end of the cylinder A, and the bent end A" is slightly curled upwardly, as shown. To cut a thread, it is 50 unwound from the spool B and drawn over the cutting-notch a.

What I claim as my invention, and desire to secure by Letters Patent, is—

1. A thread cutter, the body of which consists of an expansible split cylinder to enter the hole in a spool, with an arm having an upturned end projecting from one end of the split cylinder, the angle of the arm and its upturned end forming a thread cutting notch, 60 substantially as described.

2. A thread cutter, the body of which consists of a spring open through from end to end to pass over a sewing machine spindle, with an arm having an upturned end projecting from one end of the spring, the angle of the arm and its upturned end forming a thread cutting notch, substantially as described.

In testimony whereof I affix my signature, 75 in the presence of two witnesses, this 13th day of May, 1895.

GEORGE R. UNKEFER.

Witnesses:

J. A. OSBORNE,
H. J. MCKINNIE.
